INVENTOR

BY Victor J. Evans

ATTORNEY

WITNESS:

UNITED STATES PATENT OFFICE.

CHARLES E. STITCHER, OF BAY CITY, MICHIGAN.

ANCHOR.

Application filed July 17, 1925. Serial No. 44,339.

To all whom it may concern:

Be it known that I, CHARLES E. STITCHER, a citizen of the United States, residing at Bay City, in the county of Bay and State 5 of Michigan, have invented new and useful Improvements in Anchors, of which the following is a specification.

This invention relates to improvements in anchors particularly adapted for anchoring fishing nets, an object being to provide 10 an anchor for this purpose whose construction will insure proper holding means for nets irrespective of the character of the bottom, the anchor taking proper hold in 15 bottoms composed of hard clay, hard pan, or hard bottoms of other character.

With the above and other objects in view, the invention further includes the following 20 novel features and details of construction, to be hereinafter more fully described, illustrated in the accompanying drawings and pointed out in the appended claim.

In the drawings:—

Figure 1 is a perspective view of an 25 anchor constructed in accordance with the invention.

Figure 2 is a side view of the same.

Referring to the drawings in detail 30 wherein like characters of reference denote corresponding parts, the reference character 10 indicates the shank of the anchor which is provided at one end with an eye 11 to permit of convenient attachment to a chain or cable, while extending transversely 35 of the shank adjacent the eye is a stock 12.

The opposite end of the shank 10 carries an arm 13 which is disposed in the same longitudinal plane as the shank and extends therefrom and is shaped so as to insure

positive holding upon any type of bottom. 40 For this purpose, the arm is longitudinally curved in a direction toward the stock and is connected to the shank by a curved crown 14 having a relatively short radius. The inner face of the arm 13 is transversely flat 45 as indicated at 15 while the outer face is transversely curved and the outer end of said arm terminates in a gradually tapering peak or bill 16.

By reference to the drawing it will be 50 seen that the relative arrangement and positions of the stock and arm are such as to insure contact of the beak or bill with the bottom, while the angular position of the arm 13, as well as its curvature and cross 55 sectional shape insures penetrating means for hard or other types of bottoms.

The invention is susceptible of various changes in its form, proportions and minor details of construction and the right is 60 herein reserved to make such changes as properly fall within the scope of the appended claim.

Having described the invention what is 65 claimed is:—

An anchor comprising a shank, a stock 70 extending transversely at one end thereof, an arm extending from the opposite end of the shank in the same longitudinal plane and at an acute angle with respect to said shank, said arm also having a transversely flat inner face and a transversely rounded outer face and a gradually tapering sharp bill at the outer end of the arm.

In testimony whereof I affix my signature. 75

CHARLES E. STITCHER.
